(57) CLAIM

I claim, the ornamental design for an LED open sign with a neon appearance, as shown and described.

DESCRIPTION

This invention is intended for use as an "open sign" and can be used in both outdoor and indoor applications.

FIG. 1 is a perspective view of a LED open sign with a neon appearance.

FIG. 2 is a front view.

FIG. 3 is a rear view; and,

FIG. 4 is a front view of the lit portion only, shown removed from the sign for clarity of disclosure.
